US0D1028499S

(12) United States Design Patent (10) Patent No.: US D1,028,499 S
(45) Date of Patent:  May 28, 2024

(54) HANDBAG

(71) Applicant: CHRISTIAN DIOR COUTURE, Paris (FR)

(72) Inventor: Maria Grazia Chiuri, Paris (FR)

() Term: 15 Years

(21) Appl. No.: 35/516,722

(22) Filed: Mar. 17, 2023

(80) Hague Agreement Data

Int. Filing Date: Mar. 17, 2023

Int. Reg. No.: DM/227761

Int. Reg. Date: Mar. 17, 2023

Int. Reg. Pub. Date: Mar. 31, 2023

(51) LOC (14) Cl. 03-01

(52) U.S. Cl.

USPC D3/246; D3/232

(58) Field of Classification Search

USPC D3/232, 233, 234, 235, 243, 246, 318, D3/319, 245, 303

CPC .. A45C 1/00; A45C 3/00; A45C 3/001; A45C 3/10; A45C 13/08
